(57) **CLAIM**

The ornamental design for a beverage container dispensing cooler, as shown and described.

DESCRIPTION

FIG. 1 is a front perspective view of a beverage cooler according to the present invention.

FIG. 2 is a front elevation view of the beverage cooler of FIG. 1.

FIG. 3 is a rear elevation view of the beverage cooler of FIG. 1.

FIG. 4 is a right side elevation view of the beverage cooler of FIG. 1.

FIG. 5 is a left side elevation view of the beverage cooler of FIG. 1; and,

FIG. 6 is a top elevation view of the beverage cooler of FIG. 1.

The broken lines shown in the FIGURES are for illustration purposes only and do not form part of the claimed invention.

1 Claim, 3 Drawing Sheets
